UNITED STATES PATENT OFFICE

JOSEPH BLACK, OF ROCHESTER, NEW YORK

BACK AND CHEST PROTECTOR

Application filed October 29, 1928. Serial No. 315,319.

This invention relates to a protector adapted to be worn for protecting the back and chest from cold, one of the objects being to provide a simple and inexpensive garment of this type adapted to be worn under the outer clothing and which can be fastened readily and securely in position where it will act as an insulating medium to prevent cold air from reaching that portion of the body protected by the garment.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front perspective view of the garment in position.

Figure 2 is a rear perspective view thereof.

Figure 3 is a vertical section taken from front to rear, the garment being closed.

Figure 4 is a section on line 4—4, Figure 3.

Figure 5 is a section on line 5—5, Figure 3.

Referring to the figures by characters of reference, 1 and 2 designate the left and right back sections or panels of the garment, these being formed of stiff paper and being held 35 together by outer and inner strips 3 and 4 of fabric having an adhesive. The right and

left front sections or panels 5 and 6 are connected at the side seams to the adjacent back sections or panels by strips 7 of fabric having adhesive thereon. These strips extend both along the outside and inside surfaces of the connected parts. The shoulder seams of the garment are formed by bringing together the front and back portions of the garment at the shoulders where they are held by strips 8 of fabric having adhesive thereon, these strips extending along the outer and inner surfaces of the shoulder portions. All

50 or reinforced by fabric strips 9 which are

attached to the garment by adhesive. It is to be understood that all portions of the garment, except the connecting strips and the reinforcing edge strips are formed of tough paper and the garment produced is of such size as to be worn readily beneath the outer clothing of the user. The front portions or panels 5 and 6 are adapted to lap while the garment is in use, there being cords 10 attached to one of these portions, such as 5, 55 close to the side thereof, and being adapted to engage buttons 11 attached to the free side edge of the adjacent portion or panel 6. Thus the garment, after being placed in position, can be held tightly about the body by means of these cords 10 the free ends of 60 which are wrapped about the buttons 11. It will be noted by referring to Figure 1 that the armholes in the garment are oversize. Thus it is possible to pay out or take up the cords 10 for the purpose of adjusting the garment 65 to persons of different sizes, there being sufficient clearance in the armholes to allow for this adjustment.

As paper constitutes an excellent insulating medium for protection from cold and as it is an inexpensive material, it will be apparent that a garment such as described and made of tough paper can be very cheaply manufactured and will constitute a highly 70 efficient protection for the wearer during cold weather.

When the garment is not in use it can be readily folded into a compact bundle and easily carried in a pocket.

What is claimed is:

An all-paper garment including right and left back panels and right and left front panels, strips of tough adhesive tape joining the right front and back panels above and below the armhole formed thereby, strips of tough adhesive tape joining the left front and back panels above and below the armhole formed thereby, a strip of tough adhesive tape connecting the back panels, a binding strip of tough adhesive tape straddling and affixed to all exposed edges of the panel, buttons fastened to one of the front panels close to the free side edge thereof, buttons secured to the other front panel at points remote 95 90 95 100

from the free side edge thereof, and cords attached to the buttons on one of the panels and adapted to be wrapped in engagement with the buttons on the other front panel thereby to hold the front panels in lapped relation and adjustably connected to fit persons of different sizes, the armholes formed between the front and back panels being oversize to permit said adjustment.

13 In testimony that I claim the foregoing as my own, I have hereto affixed my signature.

JOSEPH BLACK.
